OTHER PUBLICATIONS

U.S. Appl. No. 13/237,603, filed Sep. 20, 2011 entitled Waterfowl Decoy Weight Assembly.

Primary Examiner — Catheri Oliver-Garcia

(74) Attorney, Agent, or Firm — Shumaker & Sieffert, P.A.

(57) **CLAIM**

The ornamental design for the waterfowl decoy weight assembly, as shown and described.

DESCRIPTION

FIG. 1 is a perspective view of an embodiment of a waterfowl decoy weight assembly.

FIG. 2 is a top view of an embodiment of the waterfowl decoy weight assembly.

FIG. 3 is a bottom view of an embodiment of the waterfowl decoy weight assembly.

FIG. 4 is a side view of an embodiment of the waterfowl decoy weight assembly.

FIG. 5 is a front view of an embodiment of the waterfowl decoy weight assembly.

FIG. 6 is a view of a side, opposite to the side shown in FIG. 4, of an embodiment of the waterfowl decoy weight assembly.

FIG. 7 is a rear view of an embodiment of the waterfowl decoy weight assembly; and,

FIG. 8 is a side view of an embodiment of the weight assembly along with an example floating waterfowl decoy and tether.

The broken line showing of environment in the drawings is included for the purpose of illustrating only and forms no part of the claimed design.
